Primary Examiner — Jeffrey D Asch*Assistant Examiner* — Tracey J Bell(74) *Attorney, Agent, or Firm* — Kilpatrick Townsend & Stockton LLP(57) **CLAIM**

The ornamental design for a shoe, as shown and described.

DESCRIPTION

FIG. 1 is a lateral side view of a shoe, it being understood that there is no claim being made to the sole.

FIG. 2 is a medial side view of the shoe of FIG. 1.

FIG. 3 is a top view of the shoe of FIG. 1.

FIG. 4 is a front view of the shoe of FIG. 1.

FIG. 5 is a rear view of the shoe of FIG. 1.

FIG. 6 is a bottom view of the shoe of FIG. 1; and, FIG. 7 is a front lateral perspective view of the shoe of FIG. 1.

The dash-dot broken lines between the sole and the upper and adjacent to top portions of the upper represent the boundaries of the claimed design and form no part of the claimed design.

The remainder of the shoe shown in broken lines shows subject matter that forms no part of the claimed design with broken lines showing a surface pattern within the boundaries of the claimed design being superimposed subject matter that is not included in the claim.
